CLAIM

The ornamental design for a computer screen with contour group organization of visual programming icons, as shown and described.

DESCRIPTION

FIG. 1 is a front view of a computer screen with contour group organization of visual programming icons showing our new design;

FIG. 2 is a front view of a lower portion of a computer screen with contour group organization of visual programming icons showing our new design;

FIG. 3 is an enlarged partial view of FIG. 2; and, FIG. 4 is an enlarged partial view of FIG. 2.

The broken lines in the FIGURES illustrate the computer screen and elements of the graphical user interface that form no part of the claimed design. The long dash short dash lines shown FIGS. 2, 3, and 4 illustrate respective portions of FIG. 2 shown in the respective enlarged views and form no part of the claimed design.

1 Claim, 4 Drawing Sheets
